(57) **CLAIM**

The ornamental design for a table, as shown and described.

DESCRIPTION

FIG. 1 is a perspective view of a table showing my new design;

FIG. 2 is a front elevational view thereof;

FIG. 3 is a top plan view thereof;

FIG. 4 is a right end view thereof; and,

FIG. 5 is a rear elevational view thereof.

The portions shown in broken lines in FIGS. 1, 2, 3, 4 and 5 are for environmental purposes only and form no part of the claimed design.

1 Claim, 5 Drawing Sheets
